UNITED STATES PATENT OFFICE.

ROBERT ANSON LITTLE, OF WOODSTOCK, VIRGINIA.

GRAIN HULLER.

Application filed April 24, 1923. Serial No. 634,373.

To all whom it may concern:

Be it known that I, ROBERT A. LITTLE, a citizen of the United States, residing at Woodstock, in the county of Shenandoah and State of Virginia, have invented new and useful Improvements in Grain Hullers, of which the following is a specification.

The present invention relates to a grain huller and particularly to devices for taking the hull or chaff off of such grains as oats, wheat, barley and the like. In devices heretofore used for taking the hull off of grain, and particularly in removing the hull or chaff from oats preparatory to making oatmeal therefrom or in preparing oats for feeding fowls, it has been necessary to first kiln-dry the oats thereby consuming a considerable amount of time and adding an expense to the operation.

It is an object of the present invention to provide a machine which will remove the hulls from oats and other similar grains without the necessity of first kiln-drying or otherwise treating the same.

Another object of the invention is to so construct the operating parts that the hull will be removed without breaking or abrading the kernel of the grain that is being operated upon.

A further object is to provide means whereby the dislodged hull or chaff, together with any dirt that may be mixed with the grain will be, when loosened therefrom, drawn off at each of the various stages of operation on said grain. This object is accomplished by creating a suction in the machine beneath each group of hulling devices.

Still another object is the production of suitable regulating devices to control the suction through said machine.

Other objects and advantages will appear in the course of the following specifications and claims.

In the drawings which form a part of this application, my invention is illustrated as particularly adapted to the hulling of oats, but I wish it to be understood that I do not desire to be limited in the application of my device to the hulling of any particular grain or seed, as devices of this character may be adapted to the hulling of a variety of grains, beans, peas and the like.

In the drawings:

Figure 1 is a vertical section through the

grain huller, showing the relation of the hulling discs, the suction producing fans and the hopper construction beneath each pair of discs and the accompanying fan. 60 Also showing the worm feeder for preventing clogging of the hoppers.

Figure 2 shows on an enlarged scale compared with Figure 1, a plan view of one of the runners showing the relation of the 65 various concentric rows of countersunk recesses, the recesses being shown over a part only of the disc.

Figure 3 is a fragmentary view on the same scale as Figure 2 and on line 3—3 of Figure 2, showing the relation of the 70 countersunk recesses in the upper and lower discs to each other.

Figure 4 shows a plan of the fan within its casing, showing the cut-off devices for 75 regulating the opening into the fan casing.

Referring to the drawings in detail, the same reference characters designating the same parts in all figures of the drawings;

10 designates a cylindrical casing which 80 may be formed of metal or other suitable material, said cylinder having a top or cover 11 and a bottom 12 apertured to permit the passage of the shaft 13 therethrough. The cover 11 is provided with a bearing 14 for 85 the upper end of the shaft, while the lower end of the shaft bears in a trampot 14^a formed centrally of a lever 15, pivoted at 16 to one of the legs 17 which supports the cylinder 10. Removably secured to the 90 shaft 13 by means of the set-screws 18 are under-runner discs 19 preferably of steel rotatable with the shaft 13 when power is applied thereto through the pulley 20. Within the casing and spaced a suitable 95 distance from said runners 19, are stationary discs 21 preferably of steel which may be adjusted relative to the runners 19 by adjusting bolts 22 by which said stationary plates are connected to the cylindrical casing 10. Located above each stationary disc 100 is a funnel-shaped hopper 23, preferably secured to the respective stationary discs located therebeneath and adapted to direct grain delivery thereto through the central 105 apertures 24 in said stationary discs onto the underrunner. In order to facilitate the feeding of grain to the underrunner and to prevent its clogging in passing through the hopper, there is provided on the shaft 13 a 110 plurality of feed-screws 13^a one located in each hopper. Located above each of the

hoppers except the topmost one, are fan casings 25 having apertures 26 in the bottom thereof and spouts 27 in communication therewith at one side which lead to a bin 5 28. Located within the fan casings are fans 29, said fans being attached to and rotatable with the shaft 13, the size of the aperture 26 being regulated by a cut-off 30 working in slideways 30^a and provided with a 10 handle 31 extending through apertures in the casing 10 for manipulating the same.

The runner discs 19 and the stationary discs 21 are provided on their adjacent surfaces with recesses or depressions 32 countersunk therein and arranged in concentric circles. These recesses or depressions are 15 preferably conical in shape with the slope of the sides thereof at a wide angle to the axis of the cone, in order to prevent grain becoming lodged therein and consequently 20 broken or ground by the abrading action of the relatively moving discs. The concentric rows of recesses are so arranged that a recess in one row will be opposite or approximately 25 opposite the space between the recesses and the adjacent rows so that grain passing out from the centre to the edge of the runner will be obliged at some period of passage to drop into one of these recesses. 30 The runner discs and the stationary discs are arranged progressively in closer proximity to each other toward the bottom of the machine for example, the uppermost discs may be arranged one-eighth of an inch 35 apart, the next pair of discs one-sixteenth of an inch apart, and the third pair of discs one thirty-second of an inch apart, thereby giving progressively a finer abrading action upon the hulls of the grain.

40 In operation, grain with the hulls thereon is delivered to the machine through the chute 33 and is directed by the upper hopper 23 through the aperture 24 onto the uppermost underrunner 19, the movement 45 of the grain being facilitated by the feed-screws 13^a. The grain then passes out between the discs 19 and 21 falling from time to time into the conical recesses and part of the chaff or hulls are dislodged therefrom by the relative action of the discs with the 50 countersunk recesses therein. The grain after passing between the discs falls over the edge of the lower disc of each pair and is subjected to the blast created by the uppermost fan 29. The current of air may be 55 regulated by the cut-off 30 so as to be sufficient to draw in all the chaff and dirt that has been dislodged from the grain in this first step of the operation and to avoid drawing in any of the grain. The grain then passes between the next pair of discs after which it is again subjected to the force of the current caused by the second fan. A 60 similar operation takes place in connection with the third pair of discs whereupon the

grain is deposited by the lower hopper onto the inclined bottom 12 of the machine from which it is delivered through the spout 34 to bags or other receptacles. The underrunners may be simultaneously adjusted relative to the stationary discs 21 by means of the lighter-screw 35 which is attached at one end to the lever 15 and is supported by the bracket 36 attached to the cylinder. The current set up by the fans 75 through the funnel-shaped hoppers 23 has an aspirating effect to draw off the chaff and other undesirable material.

By the peculiar construction of the countersunk recesses in the discs, the grain passing out between a pair of said discs is permitted to drop endwise into the recesses in the lower disc and to be operated upon by the recessed upper disc, whereby a rubbing effect takes place and the hulls are dislodged 80 from the grain by the continuous friction, but by constructing these recesses of conical shape and with a wide angle to the perpendicular, the grain will not be retained in the recesses so that it cannot be readily displaced. Consequently there will be no 85 grinding effect on the grain which would result in the grain being broken or abraded by the action of the cooperating discs, but there will be such an agitation and rubbing 90 of the grain as to dislodge the hulls without injuring the grain.

95 By locating an aspirating fan beneath each pair of discs the dirt and hulls dislodged therefrom by each succeeding pair of discs will be carried off to the bin 28 and will not be passed between the next succeeding pair of discs. By this arrangement the grain is delivered to each succeeding pair of discs in a cleaner condition than it otherwise would and the hulls and dirt are not present to interfere with or clog the next succeeding discs. When the grain has passed through the machine the hulls will not only have been dislodged from the 100 grain, but will also have been separated therefrom at each progressive stage.

105 What I claim as new is;

1. In a grain huller, a plurality of hoppers located one above the other, a pair of discs beneath each hopper, the adjacent faces of each pair lying in parallel planes and having conical recesses formed therein and one of said discs being rotatable.

110 2. In a device of the character described, a plurality of hoppers one above the other, pairs of discs beneath each of said hoppers, a fan enclosed on all sides by a casing having an aperture in the bottom thereof located beneath each of said pairs of discs and above the next succeeding hopper, and means for rotating one of each of said pairs of discs and said fans.

115 3. In a device of the character described, a casing, a plurality of hoppers one above 120

the other, pairs of discs beneath said hoppers, an apertured fan casing having a fan therein located beneath each of said pairs of discs and above the next succeeding hopper, means for rotating one disc of each of said pairs and said fans, and means for varying the size of the aperture in the fan casings.

4. A device of the character described, comprising, a plurality of funnel-shaped hoppers located therein one above another, pairs of discs located beneath said hoppers, the lower disc of each pair being rotatable and the upper disc of each pair being stationary, fans located beneath each pair of discs and fan casings surrounding said fans and opening into said hoppers, a shaft supporting said rotatable discs and fans, and means for adjusting said rotatable discs relative to the stationary discs.

5. A device of the character described, comprising a casing, a plurality of frusto-conical hoppers located in said casing one above another, a stationary disc beneath each hopper, a rotatable shaft journaled to extend centrally through said hoppers having discs thereon corresponding to each of said stationary discs and rotatable with said shaft, apertured fan casings beneath each pair of discs having fans therein rotatable with said shaft, said pairs of discs having conical recesses formed therein arranged in concentric circles, the recesses of each circle being opposite to the space between the recesses of the adjacent circles, and means for adjusting said shaft.

6. In a grain huller, a plurality of hoppers located one above the other, a pair of discs beneath each hopper having their active faces in parallel planes, the adjacent faces of each pair having conical recesses formed therein and one of said discs being revolvable, a revolvable shaft extending through said hoppers and a feed-screw on said shaft corresponding to and located in each hopper.

7. A device of the character described, comprising a casing, a plurality of frusto-conical hoppers located in said casing one above another, a stationary disc beneath each hopper, a rotatable shaft journaled to extend centrally through said hoppers having discs thereon corresponding to each of said stationary discs and rotatable with said shaft, apertured fan casings beneath each pair of discs having fans therein rotatable with said shaft, a feed-screw on said shaft corresponding to and located in each hopper, said pairs of discs having conical recesses formed therein arranged in concentric circles, the recesses of each circle being oppo-

site to the space between the recesses of the adjacent circles, and means for adjusting said shaft.

8. In a grain huller, a pair of discs arranged in spaced relation to each other, the space between said discs being such as to accommodate the grain to be hulled, said discs having conical depressions formed in their adjacent faces and one of said discs being rotatable.

9. In a grain huller, a pair of discs arranged in close proximity to each other, but spaced a sufficient distance apart to accommodate therebetween the grain to be hulled, one of said discs being rotatable and having conical depressions in the face thereof adjacent the other disc.

10. A device of the character described, comprising a pair of discs, one of which is rotatable, a fan casing lying beneath said pair of discs and having an opening in the bottom thereof, spouts leading from said fan casing to a point beyond the periphery of said pair of discs.

11. A device of the character described, comprising a pair of discs having their adjacent surfaces in parallel planes one of said discs being rotatable and provided with conical depressions in the face thereof adjacent the other disc, and means for adjusting said discs toward and away from each other.

12. A device of the character described, a pair of relatively rotatable discs, depressions in one of said discs arranged in concentric circles, the depressions of each circle being opposite the spaces between the depressions of the adjacent circles.

13. A device of the character described, comprising a pair of spaced apart relatively moving surfaces, one of which is provided with conical depressions.

14. A device of the character described, comprising a pair of spaced apart relatively moving surfaces, one of which is provided with conical depressions, and means for delivering the grain to be hulled between said surfaces.

15. In a device of the character described, a pair of spaced apart relatively moving surfaces, one of said surfaces having conical depressions therein, the walls of which are at a wide angle to their axes.

16. In a device of the character described, a pair of spaced apart relatively moving surfaces having conical depressions therein, the walls of which are at a wide angle to their axes.

In testimony whereof I have hereunto set my hand.

ROBERT ANSON LITTLE.
